UNITED STATES PATENT OFFICE.

CHARLES V. HULMES, OF MECHANICSBURG, OHIO, ASSIGNOR OF ONE-HALF
TO CHARLES W. MARTIN AND THOMAS MARTIN, OF SAME PLACE.

DEVICE FOR TOASTING BREAD.

SPECIFICATION forming part of Letters Patent No. 465,666, dated December 22, 1891.

Application filed April 24, 1891. Serial No. 390,216. (No model.)

To all whom it may concern:

Be it known that I, CHARLES V. HULMES, a citizen of the United States, residing at Mechanicsburg, in the county of Champaign and 5 State of Ohio, have invented certain new and useful Improvements in Devices for Toasting Bread, of which the following is a specification.

My invention relates to improvements in 10 devices for toasting bread; and it is especially adapted for use with gasoline or other vapor stoves, the object of the invention being to provide a simple device which may be placed over an ordinary gas or vapor burner 15 and support the bread in a convenient and suitable position for toasting.

My invention consists in the constructions and combinations of parts hereinafter described, and set forth in the claim.

20 In the accompanying drawings, which form a part of this specification, Figure 1 is a perspective view of a device embodying my invention. Figs. 2 and 3 are respectively a side and sectional elevation of the same. Fig. 4 25 is a plan view with the supporting wires or mat removed. Fig. 5 is a small detail of a portion of the outer frame, showing the manner of attaching the supporting wires or mat.

Like parts are indicated by similar letters 30 of reference in the several views.

In the said drawings, A A represents an outer frame or casing, which consists, preferably, of a rectangular pan formed of sheet-iron or other suitable material with four projecting sides *a a* and provided at one side with a projecting handle B, secured to one of the projecting sides. The bottom *b* of this supporting frame or pan is provided with a series of openings or perforations *c*, which extend outwardly from a central solid portion *b'* to the sides *a*, the perforations being gradually enlarged as they extend outwardly from the center, those near the central part of the bottom being small, and the sizes gradually increased toward the respective edges of the frame or pan. Arranged above the perforated bottom *b* at a suitable height, and supported on the top of the projecting sides *a a*, is a series of supporting-wires *d d'*, which extend in opposite directions from side to side of the main frame or pan A A, these wires

being preferably woven in the form of a mat with large meshes, as shown in Figs. 1 and 3. The ordinary woven wire cloth or fabric with large meshes may be used.

To provide for holding the supporting-wires in place, I preferably form the projecting edges *a* with an outwardly-extending flange *a'* at right angles to the respective sides and parallel with the bottom *b*. These flanges *a'* are made to project sufficiently to receive the respective ends of the supporting-wires and be turned or doubled over the same, as shown in Fig. 5, and thus firmly secure the supporting-wires in place.

In operation the device is placed over a burner with the plain or solid portion *b'* of the bottom immediately over the burning gas or vapor. The flame of the burner is thus spread along the under surface of the pan, 70 the heat therefrom passing up through the perforations, the inner perforations being sufficiently small to prevent the blaze from passing through, while the outer perforations, being out of the radius of the flame, permit all 75 of the heat products to pass through the bottom into the pan or frame. The bread to be toasted is placed upon the supporting-wires in a convenient position and within reach of the attendant. The projecting sides prevent 80 all side drafts, thus causing all heat products to pass directly up in contact with the under surface of the bread, which is thus readily and evenly toasted.

Having thus described my invention, I 85 claim—

The combination of an outer pan or casing, the bottom of which is formed with a central deflecting portion and an outer perforated portion, said perforations being increased in 90 size toward the outer edges, and the supporting wires arranged above said perforated bottom and connected to the projecting sides of said pan or casing by overlapping flanges, substantially as specified.

In testimony whereof I have hereunto set my hand this 16th day April, A. D. 1891.

CHARLES V. HULMES.
